DESIGN FOR A TOILET FLUSH TANK

Olley C. Lauber, Archbold, Ohio

Application September 25, 1935, Serial No. 58,709

Term of patent 14 years

To all whom it may concern:

Be it known that I, Olley C. Lauber, a citizen of the United States, residing at Archbold, in the county of Fulton and State of Ohio, have invented a new, original, and ornamental Design for a Toilet Flush Tank, of which the following is a specification, reference being had to the accompanying drawing, forming part thereof, and in which:

Fig. 1 is a perspective view of a toilet flush tank showing my new design.

Fig. 2 is a top plan view of the same.

The dominant feature of the design resides in the top of the flush tank.

I claim:

The ornamental design for a toilet flush tank, as shown and described.

OLLEY C. LAUBER.
